William Pountney, of New York, N.Y.
Letters Patent No 1258, dated June 19, 1860.

The schedule referred to in these Letters Patent and making part of the same.

To all whom it may concern.

Be it known that I, William Pountney, of the City of New York, Machinist, have invented a new and original design for the Manufacture of Decanter Stoppers, and I declare the following, is a full and exact description of the same.

The accompanying drawings represent the design and form of the Decanter Stopper.

Des. 1258

Fig. I. being a front view.

Fig. II & III. a side view, and

The design which I have invented and adapted for the Decanter Stopper is that of a Fireman's Cap or Helmet.

This is made of composition metal, or metal to be plated with Gold or Silver. The design is in the upper part of the Stopper.

The design is fully expressed and described by calling it a Fireman's Cap or Helmet in miniature. It should be made with a broad brim (c) longer behind than in front, curved upwards at the sides, and downwards in front and behind. The frontlet or shield (a) may have upon it any number, scroll or device, that may be desired. The crown or body of the Cap (d) is conical and pointed at the apex and is ribbed upon the sides, so as to give the completest resemblance to a Fireman's Cap or helmet.

What I claim in the foregoing is the forming and designing of the upper part of a decanter stopper in the shape of a Fireman's Cap or Helmet, as set forth and described.
